UNITED STATES PATENT OFFICE

134,455

DESIGN FOR A REFRIGERATOR CABINET

John H. Ganzer, Duluth, Minn., assignor to The
Coolerator Company, Duluth, Minn., a corpora-
tion of Minnesota

Application April 13, 1942, Serial No. 106,558

Term of patent 7 years

To all whom it may concern:

Be it known that I, John H. Ganzer, a citizen of the United States, residing at Duluth, in the county of St. Louis and State of Minnesota, have invented a new, original, and ornamental Design for a Refrigerator Cabinet, of which the following is a specification, reference being made to the accompanying drawing, forming a part thereof, in which:

Fig. 1 is a front elevational view of a refrigerator cabinet embodying my new design;

Fig. 2 is a side elevational view thereof as seen from the right-hand side of Fig. 1; and

Fig. 3 is a top plan view thereof.

The characteristic feature of my design resides in a refrigerator cabinet of substantially the configuration shown, the doors of which have flat front surfaces, the extremities of the upper and lower doors each having a flat surface in the same horizontal plane with the top and bottom of the refrigerator cabinet, and each door having rounded side edges merging into flat surfaces which lie in the same vertical plane as the sides of the cabinet.

I claim:

The ornamental design for a refrigerator cabinet, substantially as shown and described.

JOHN H. GANZER.
